Primary Examiner — Elizabeth J Oswecki(57) **CLAIM**

The ornamental design for an electronic locker lock, as shown and described.

DESCRIPTION

FIG. 1 is a front, left perspective view of a first embodiment of an electronic locker lock showing my new design;
FIG. 2 is a top plan view thereof;
FIG. 3 is a left side elevation view thereof;
FIG. 4 is a front elevation view thereof;
FIG. 5 is a right side elevation view thereof;
FIG. 6 is a bottom plan view thereof;
FIG. 7 is a front, left perspective view of a second embodiment of an electronic locker lock showing my new design;
FIG. 8 is a top plan view thereof;
FIG. 9 is a left side elevation view thereof;
FIG. 10 is a front elevation view thereof;
FIG. 11 is a right side elevation view thereof; and,
FIG. 12 is a bottom plan view thereof.
Features shown in dashed lines are not part of the claimed design.
